UNITED STATES PATENT OFFICE

LEWIS MOE, OF BATTLE LAKE, MINNESOTA

STOVE AND FURNACE

Application filed June 9, 1928. Serial No. 284,254.

This invention relates to new and useful improvements in stoves and furnaces.

It is a well known fact that in ordinary stoves and furnaces the products of combustion pass directly from the fire pot to the chimney flue, and that these products carry off an extremely large amount of heat which is therefore not utilized to heat the room in which the stove is located. This condition, therefore, requires the consumption of more coal or other heat producing elements than should be necessary to raise the temperature in a room to a desired degree. Also, the extremely hot products of combustion which directly enter the chimney flue often cause chimney fires.

One of the principal objects of my invention is to provide a stove or furnace with a hollow jacket of a construction which will cause the hot products of combustion to travel a comparatively long distance between the fire pot and the flue whereby an increased amount of heat will be radiated than heretofore with the same amount of coal consumption, and whereby said products of combustion will be materially cooled by the time they enter the flue and the danger of chimney fires thereby reduced to a minimum.

Another object lies in the provision of a jacket for the purpose described which is in the nature of an attachment for ordinary stoves or furnaces, thus permitting the ready installation of my invention to stoves or furnaces now in use.

With these and other objects in view which will more fully appear, the nature of the invention will be more clearly understood by following the description, the appended claims, and the several views illustrated in the accompanying drawings.

In the accompanying drawings which illustrate one form of my invention:

Fig. 1 is a front elevation showing the application of my invention to an ordinary heating stove,

Fig. 2 is a side elevation thereof, a portion being shown in section,

Fig. 3 is a vertical sectional view taken on the line 3—3 of Fig. 2,

Fig. 4 is a horizontal sectional view taken on the line 4—4 of Fig. 1,

Fig. 5 is a vertical sectional view taken on the line 5—5 of Fig. 1,

Fig. 6 is a horizontal sectional view taken on the line 6—6 of Fig. 5, and

Fig. 7 is a detail vertical sectional view through the jacket showing the damper.

Like reference numerals designate corresponding parts throughout the several figures of the drawings.

Referring to the drawings, I have illustrated a heating stove A which is surrounded by a hollow jacket B forming the subject matter of my invention. The jacket B comprises a cylinder surrounded on three sides by a double wall construction and on the fourth side by doors 22 and 23. It is to be understood that my invention is adapted to be attached or applied to various types of stoves or furnaces, and that the term "stove" is intended to embrace any of such types.

The stove A includes the usual casing having the usual top lid (not shown) and an outlet 10 for the products of combustion, although it will be understood that a stove or furnace of any desired construction may be employed.

The jacket B is preferably formed of sheet metal and includes outer side walls 11, 12, an outer rear wall 13, inner side walls 14, 15 which are respectively spaced from the outer side walls 11, 12 to form vertical passages 16, 17 respectively, and an inner rear wall 18 which is connected to the inner side walls 14, 15 and spaced from the outer rear wall 13 to form a vertical rear passage 19 which is in open communication with the side passages 16, 17. The fronts of the side passages 16, 17 are closed by vertical walls 20, 21 respectively, and at the front of the jacket between the walls 20 and 21 are doors 22, 23 which are hinged to the jacket to open outwardly for the purpose of gaining access to the stove. These doors preferably extend the entire height of the jacket and thereby permit ready access to either the fire or ash pit doors which are not shown. Disposed within the hollow jacket formed by the walls 14, 15, 18 and doors 22, 23 is a cylinder 24 which

embraces the stove A. The front of the cylinder 24 is provided with upper and lower doors 24^a and 24^b. Lateral passages 25, 26 afford communication between the interior of the cylinder 24 and the vertical side passages 16 and 17 respectively. These passages 25, 26 are centrally located between the front and rear walls of the jacket, and at the extreme upper portion of said jacket. The jacket includes a removable and imperforate top 27 which extends between and merges with the outer side walls 11 and 12, the front walls 20, 21 and the rear outer wall 13. The inner side walls 14, 15 and the inner rear wall 18 are also united at their upper edges to said top 27. The lower portions of the vertical passages 16, 17 and 19 are closed by bottom walls 28, 29 and 30 respectively.

Located in the rear of the jacket and at the upper end of and in direct communication with the vertical rear passage 19 is an outlet 31 which is adapted for connection with the chimney flue and which is provided with a damper 31^a. Located in the respective vertical side passages 16 and 17 between the lateral passages 25, 26 and the vertical rear passage 19, are downwardly extending baffle plates 32 and 33, the upper ends being united with the top 27, the lower ends being curved forwardly as at 34, 35 and terminating above the bottom walls 28, 29 of the vertical side passages 16, 17, and the sides of the baffle plates being united with the associated inner and outer side walls of the jacket.

From the foregoing, it will be observed that the products of combustion will pass outwardly from the stove A into the cylinder 24 and thence laterally in opposite directions through the lateral passages 25 and 26 into the vertical side passages 16 and 17. The products of combustion will then pass downwardly through the vertical side passages 16 and 17 and thence around or under the baffles 34 and 35, thence rearwardly into the vertical rear passage 19, and thence outwardly to the flue through the outlet opening 31. By thus causing the products of combustion to divide as they pass in their circuitous routes from the fire box of the stove to the flue outlet 31, I have thereby divided the products of combustion into two streams whereby they will not only function to radiate considerably more heat than heretofore, but will also function to better cool the products of combustion before they pass outwardly into the chimney.

In order to permit of the removal of such of the heavier particles of combustion which settle in the bottom of the vertical rear passage 19, I have provided clean-out openings 36, 37 which are respectively formed in the outer side walls 11 and 12 adjacent the bottom wall 30, and associated with these openings are closures 38 and 39 of any suitable construction.

When starting the fire in the stove, it may be desirable to have direct communication between the stove and the outlet 31, and to this end, I have provided an opening 40 in the cylinder 24 at a point in registration with the outlet 31. The opening 40 is in communication with the outlet 31 through the medium of a rearwardly extending lateral passage 41. The opening 40 is controlled by a damper 42 which is fixed to a horizontal shaft 43 journaled in the jacket and having one end extending beyond the jacket and terminating in a handle 44.

When applying the jacket B to the stove A, the top 27 of the jacket is removed, and the stove inserted within the cylinder 24 of the jacket through the open top thereof. The stove is supported by cross bars 45, 45 fixed to the lower portion of the jacket and extending across the cylinder 24.

It is of course to be understood that the details of structure and arrangements of parts may be variously changed and modified without departing from the spirit and scope of my invention.

I claim:

1. The combination with a stove having an exit opening for the products of combustion, of a heating attachment therefor comprising a hollow jacket surrounding said stove, said jacket provided with vertical side passages, and a vertical rear passage for connection to the smoke flue, each side passage opening into the interior of said jacket at its upper end and provided with a baffle extending from the top toward the bottom of each said side passage and separating each said side passage from said rear passage, whereby the products of combustion will be conducted from the exit of said stove downwardly through said side passages, below said baffles and upwardly through said rear passage to the smoke-flue.

2. In combination a stove having an exit opening for the products of combustion, a heating attachment comprising an inner shell surrounding said stove and an outer shell, said outer shell provided with side and rear vertical passages, said rear passage opening into a smoke-flue, said side passages connected by horizontal passages to the interior of said inner shell near its top, baffles extending downward from the top of said side passages and separating the same from the vertical rear passage, whereby the products of combustion are conducted from the stove exit into the upper ends of said passages, thence downwardly below said baffles and upwardly through said rear passage to said smoke-flue.

3. In combination a stove having an exit opening for the products of combustion, a heating attachment comprising an inner shell surrounding said stove and an outer shell, said outer shell provided with side and rear

vertical passages, said rear passage opening into a smoke-flue, said side passages connected by horizontal passages to the interior of said inner shell near its top, baffles extending downward from the top of said side passages and separating the same from the vertical rear passage, the space between the rear passage and the inner shell forming a cold air passage extending into said smoke-flue.

10 4. In combination a stove having an opening for exit of products of combustion, a heater jacket surrounding said stove and comprising an inner and an outer shell, partitions separating said shells to provide vertical rear and side passages, said side passages and inner shell being closed at the top and provided with connecting passages, baffles extending from the top of said side 15 passages downwardly to near the bottom thereof and separating the same from the rear passage, said side passages and rear passage being closed at the bottom and said rear passage extending upwardly for connection to a 20 flue.

25 5. In combination a stove having an opening for exit of products of combustion, a heater jacket surrounding said stove and comprising an inner and an outer shell, partitions separating said shells to provide vertical rear and side passages, said side passages and inner shell being closed at the top and provided with connecting passages, baffles 30 extending from the top of said side passages downwardly to near the bottom thereof and separating the same from the rear passage, said side passages and rear passage being closed at the bottom and said rear passage extending upwardly for connection to a flue, 35 said inner shell being open at its bottom, and the space between said inner shell and said rear passage providing a cold air passage also extending upward for connection with the flue.

40 45 6. In combination a stove having an opening for exit of products of combustion, a heater jacket surrounding said stove and comprising an inner and an outer shell, partitions separating said shells to provide vertical rear and side passages, said side passages and inner shell being closed at the top and provided with connecting passages, baffles 45 extending from the top of said side passages downwardly to near the bottom thereof and separating the same from the rear passage, said side passages and rear passage being closed at the bottom and said rear passage extending upwardly for connection to a flue, and a damper controlled passage 50 extending through said jacket from the stove exit to the upper end of said rear passage.

60 In testimony whereof, I have hereunto subscribed my name.

LEWIS MOE.
